CLAIM

The ornamental design for a combined control unit holder with upright support and base for a mobile radiotelephone set, as shown and described.

DESCRIPTION

FIG. 1 is a front, top and right side perspective view of a combined control unit holder with upright support and base for a mobile radiotelephone set showing my new design;

FIG. 2 is a right side, front and top and front perspective view thereof;

FIG. 3 is an enlarged, left side and rear and bottom perspective view of the combined control unit holder with the upright support shown in truncated form for facility of illustration;

FIG. 4 is a left side, front and bottom perspective view of the truncated assembly showing in FIG. 3; and,

FIG. 5 is a rear, top and right side perspective view of the assembly shown in FIG. 1.
